CONTAINER FOR BOXES OF FILM SLIDES OR THE LIKE

James R. Walsh, 2 Coventry-on-Duxbury, Plum Grove
Village, Rolling Meadows, Ill. 60008

Filed Oct. 6, 1972, Ser. No. 295,478

Term of patent 14 years

Int. Cl. D3—99

U.S. Cl. D87—1 D

FIG. 1

FIG. 4

FIG. 3

FIG. 1 is a perspective view of a container for boxes of film slides or the like showing my new design;

FIG. 2 is a side elevation;

FIG. 3 is a top plan view with the cover removed; and

FIG. 4 is an enlarged, fragmentary cross-sectional view taken along line 4—4 of FIG. 1.

I claim:

The ornamental design for a container for boxes of film slides or the like, as shown.
